UNITED STATES PATENT OFFICE.

IRVING B. HIPPMAYER, OF WAUKEGAN, ILLINOIS, ASSIGNOR TO THE CREAMERY PACKAGE MFG. COMPANY, OF CHICAGO, ILLINOIS, A CORPORATION OF ILLINOIS.

CASE-WASHING MACHINE.

Application filed June 23, 1924. Serial No. 721,714.

The invention relates to machinery for washing the cases or crates in which bottles are handled, with reference more particularly to milk bottle cases.

5 The handling of bottled milk between the dairy plants and their customers is generally accomplished with the use of cases holding a quantity of bottles. The empty bottles are collected and replaced in the crates for return 10 to the dairy plants. Before the bottles are refilled with milk they are generally removed from the cases and washed in machines adapted to that purpose, being then refilled and again placed in cases. During the period 15 in which the bottles are being washed, it is desirable also to wash the cases before the refilled bottles are replaced in them. The case washing operation should thoroughly cleanse the cases on all sides for the removal of any 20 soil accumulated upon them before they are again put in service.

It is the principal object of this invention to provide a machine through which bottle cases may be conveyed in an end to end series 25 for spray washing, and so handled by the conveying mechanism within the machine that all surfaces of the cases are exposed during their passage through the machine to the cleansing action of the spraying devices provided therein.

Other objects and advantages will be apparent in the following detailed description of a preferred embodiment of the invention which has been selected for illustration in the 35 accompanying drawings. It will be understood, however, that various changes in form, construction and arrangement may be made by those skilled in the art without departing from the scope and spirit of the invention as 40 expressed in the appended claims.

In the drawings, Fig. 1 represents a plan view of the machine with the top covering removed. Fig. 2 is a sectional elevation of the machine taken through the center of the 45 tank and looking toward the side of the latter supporting the operating mechanisms. Fig. 3 is a front end view of the machine. Fig. 4 is a cross sectional elevation taken on the plane of the line 4—in Fig. 1 and illustrating 50 the arrangement of the spray pipes in relation to the conveying means.

The machine comprises a tank 1 supported upon upright standards 2 secured at intervals to the opposite lateral walls of the tank. The

tank is adapted to contain a quantity of washing solution in its lower portion to be applied to bottle cases passed through the upper portion of the tank. Bottle cases entering the machine are received upon a series of spaced rollers 3 positioned at the front end of the tank and extending partially into the tank, the rollers 3 being pivoted in a pair of lateral supporting bars 4 mounted on suitable brackets secured to the side walls of the tank. The rollers are arranged in downwardly inclined serial relation for the movement of cases thereover by gravity.

Positioned inwardly of the series of rollers 3 is a driven chain conveyor of which the upper operating run is inclined, first upwardly and then downwardly. The doubly inclined conveyor comprises a pair of laterally spaced chains 5 and 6 supported at the end adjacent the series of rollers by a pair of sprockets 7 and 8 mounted upon an idler 75 shaft 9 journalled in suitable bearings supported on the side walls of the tank. The upper runs of the chains 5 and 6 are also operatively supported on a central pair of sprockets 10 and 11 positioned substantially 80 above the end sprockets 7 and 8, the center sprockets 10 and 11 being supported on an idler shaft 12 journalled in suitable end bearings mounted on the side walls of the tank. The opposite ends of the operative runs of the chains 5 and 6 are supported on a pair of driving sprockets 13 and 14, positioned substantially below the central sprockets 10 and 11. The driving sprockets 13 and 14 are secured on a drive shaft 15 90 journalled in suitable bearings mounted on the side walls of the tank. One end of the drive shaft 15 extends outwardly of the side wall of the tank for connection with driving means hereinafter described.

A second pair of conveying chains 16 and 17 are operatively positioned endwardly adjacent the chains 5 and 6. The second pair of chains 16 and 17 are supported for operation on an upward inclination and are adapted to receive the cases from the downwardly inclined portions of the chains 5 and 6. The chains 16 and 17 are supported at the inner ends of their runs by a pair of sprockets 18 and 19 secured to a shaft 20 journalled in 95 suitable bearings mounted on the side walls of the tank. The chains 16 and 17 are supported at the upper and outer ends of their

runs upon a pair of sprockets 21 and 22 mounted upon an idler shaft 23, journalled in suitable bearings supported upon the side walls of the tank. The lower inner shaft 20 is driven by a sprocket 24 mounted thereon outwardly of the conveyor chain sprockets, and operatively connected by a chain 25 with a sprocket 26 secured on the drive shaft 15.

Another series of rollers 27 is provided at 10 the rear end of the machine to receive the cases from the chains 16 and 17. The rollers 27 are positioned in spaced relation and pivotally supported in side rails 28 and 29 carried by brackets mounted on the side walls of 15 a rearwardly extended canopy 30 supported on the end wall of the machine. The bottle cases are laterally guided in their passage through the machine by a pair of guide rails 31 and 32 supported by brackets 33 secured to 20 the side walls of the tank. The carrying runs of the two pairs of chains are supported between their operating sprockets upon the pairs of under-positioned guide plates 34, 35 and 36, secured to suitable brackets mounted 25 on the tank side walls.

Spaced inwardly from the front end of the machine is a spray supply pipe 37 extending across the tank beneath the series of rollers 3, and connecting with a riser pipe 38 which in 30 turn is connected with an overhead cross pipe 39, the latter being connected with a downwardly extending laterally positioned pipe 40. The lateral and overhead sections are provided with spray openings for the discharge 35 of the washing solution upon the side surfaces and the upper and inner surfaces of the passing cases. A branch pipe connection 41 extends from the supply pipe 37 inwardly adjacent the end of the series of rollers 3, and 40 is there connected with a cross pipe 42 positioned transversely and beneath the path of the cases.

The cross pipe 42 is provided with upwardly directed spray openings. As the cases, represented in the drawings by the letter A, pass 45 downwardly over the inclined rollers 3, and are received by the upwardly inclined run of the conveyor chains 5 and 6, it will be observed, as illustrated in Fig. 2, that the adjoining 50 cases are tipped in endward relation to each other, so that their end surfaces are fully exposed to the discharge of the solution from the cross pipe 42, thus effecting the thorough cleansing of the end surfaces, an action 55 which is not possible when the cases are moved through spraying baths on the same plane and in abutting relation.

Another supply pipe 43 is positioned inwardly of the rear end of the tank and is 60 connected with a laterally positioned riser pipe 44 which leads to an overhead cross pipe 45 and therefrom to a downwardly positioned lateral pipe 46, the upright and overhead sections being inwardly provided with spray 65 openings to effect a second washing of the

lateral surfaces and inner surfaces of the passing cases. A branch pipe 47 leading from the supply pipe 43 connects with a second cross pipe 48 having upwardly directed spray openings and positioned adjacent the meeting 70 point of the angularly related runs of the downwardly inclined rear portion of the conveyor chains 5 and 6 and the upwardly inclined chains 16 and 17. The passing cases are at this point again endwardly tilted so that the washing spray from the cross pipe 48 is thoroughly applied to the end surfaces of the passing cases.

The latter are carried by the conveyor chains 16 and 17 upwardly to the series of 80 rollers 27 and directed out of the machine. As the cases reach the rollers 27, they may be subjected to a cooling rinse bath sprayed upon them from a pipe 49 extending around the four sides of the path of the cases, and having suitable openings for the direction of lateral sprays upon the cases. It will be noted also that as the cases enter the area of the rinsing spray their ends are upwardly separated so that the end surfaces of the cases are rinsed 90 as well as the side surfaces.

The chains may be operatively driven and the washing sprays supplied from the solution contained in the tank by any suitable means, that herein illustrated comprising as a prime source of power a motor 50, mounted on a suitable platform 51 secured to the tank structure, and having endwardly extended shafts 52 and 53 operatively connected with the rotors of the respective pumps 54 and 55 drawing solution through the screened inlet pipes 56 and 57 from the interior of the tank. The pumps 54 and 55 discharge the solution under pressure through the screened outlet connections 58 and 59 to the respective supply pipes 37 and 43 within the tank. The motor shaft 53 also carries a pulley 60 connected by a belt 61 to a pulley 62, mounted on a shaft 63 journalled in a casing 64, suitably supported on the side of the tank. The 110 casing 64 encloses a conventional worm and spiral-gear drive for the transmission of power from the shaft 63 to the sprocket drive shaft 15 extending into the casing, whereby the conveyor chains are operatively driven. 115 The upper side of the tank is preferably enclosed by sections of removable covers 65 suitably supported at the upper extremities of the side walls of the tank.

The rinsing spray pipe 49 may be supplied 120 with cold rinse water by suitable connection with an independent supply of cold water (not shown).

Water for the solution within the tank may be supplied by the valve controlled inlet 125 pipes 66 and 67 commonly connected with a source of water supply. The solution may be maintained at suitable temperature by means of the steam injectors 68 and 69, extending into the tank and outwardly connected 130

through the valve controlled pipes 70 and 71 with a suitable source of steam supply.

I claim as my invention:

1. A case washing machine, comprising a tank adapted to contain washing fluid, a downwardly inclined gravity conveyor supported within and at one end of said tank and adapted for the movement of a series of cases into said tank, an endless conveyor belt 10 operatively supported in the central portion of said tank having a doubly inclined carrying run adapted to receive cases from said gravity conveyor, said carrying run extending upwardly from adjacent the lower end 15 of said gravity conveyor and downwardly toward the opposite end of said tank, a second endless conveyor belt operatively supported in said tank having an upwardly inclined carrying run positioned endwardly adjacent the downwardly inclined portion of said first conveyor belt and adapted to receive cases therefrom, and spraying devices positioned adjacent the lower ends of said conveyor carrying runs adapted to spray washing fluid upon the exposed ends of said cases 20 passing in angularly tilted relation from the downwardly inclined to the upwardly inclined portions of said conveyors.
2. A case washing machine comprising a tank adapted to contain washing fluid, an endless conveyor belt operatively supported in said tank having a doubly inclined carrying run adapted to receive cases, said carrying run extending upwardly from one end 35 and downwardly toward the opposite end, a
- second endless conveyor belt operatively supported in said tank, having an upwardly inclined carrying run positioned endwardly adjacent the downwardly inclined portion of said conveyor belt and adapted to receive cases therefrom, and spraying devices positioned adjacent the lower ends of said conveyor carrying runs adapted to spray washing fluid upon the exposed ends of said cases passing thereover in angularly tilted 40 relation.
3. A case washing machine, comprising a tank adapted to contain washing fluid, a sectional conveyor operatively supported in said tank, one section of said conveyor including an endless belt having a downwardly inclined run, another section of said conveyor including an endless belt having an upwardly inclined run, said sections being positioned so that the lower ends of the zones of travel 50 of the inclined runs of said endless belts respectively terminate in adjacent spaced relation, said endless belts being adapted to move a series of cases through said tank in successive relation and to tilt said cases in 55 passing from one to the other of said belts so that the end surfaces of adjacent cases are separated in passing over the space between the ends of said inclined runs, and means for spraying washing fluid upon said end surfaces while passing over said space.

In witness whereof I have hereunto attached my signature.

IRVING R. HIPPENMEYER.
